UNITED STATES PATENT OFFICE.

ELEAZAR J. BEARD, OF ST. LOUIS, MISSOURI, ASSIGNOR TO HIMSELF AND
GEORGE N. BEARD, OF SAME PLACE.

IMPROVEMENT IN COTTON-BALE TIES.

Specification forming part of Letters Patent No. 129,917, dated July 30, 1872.

To all whom it may concern:

Be it known that I, ELEAZAR J. BEARD, of St. Louis, in the county of St. Louis and State of Missouri, have made a certain new and useful Improved Cotton-Bale Tie; and I do hereby declare that the following is a full and true description thereof, reference being had to the accompanying drawing and to the letters of reference marked thereon.

This invention relates to bale-ties or couplings for fastening metallic bands for cotton-bales or other purposes. It consists in forming a sleeve-coupling having an open edge for the passage of the bands, which are inserted laterally, and retained in the oblong opening of the sleeve by its flanges, all of which will now more fully appear.

To enable those herein skilled to make and use my said improvement, I will now more fully describe the same, referring to—

Figure 1 as an isometrical view, showing bands in a lock. Fig. 2 is an end view of the sleeve-coupling.

The bale-tie A consists of a bar of metal, rolled, with flanges a^1 on each edge, and bent, forming the sleeve-coupling, clearly shown in Fig. 1. The flanges a^1 form the entrance or opening a^2 . Through said opening a^2 the looped ends of the bands are passed into the oblong opening of the sleeve-coupling, disengagement of the bands being pre-

vented by the flanges a^1 . The flanges may be beveled or chamfered off, as indicated in Fig. 2, so as to allow the more ready entrance of the bands.

It will be noted that in this improvement there is, in forming same, no waste of metal, the flanges being formed on the edges of bar when rolled. The bar is of sufficient width to form the length or size of couplings, and the remaining process is to cut off to desired length and simply bend the coupling-pieces into the sleeve form shown in Fig. 1.

My improved coupling or tie piece is simple, cheap, compact, and by its use an easy adjustment and locking of bands is achieved—advantages over ordinary ties or devices readily apparent.

Having thus fully described my said invention, what I claim is—

1. A sleeve-coupling, A, formed with flanges a^1 and opening a^2 , substantially as set forth.
2. The combination of the coupling A, formed as described, with metallic bands, as and for the purpose set forth.

In testimony of said invention I have hereunto set my hand.

ELEAZAR J. BEARD.
